ELECTRICAL CONNECTION

Walter McGinnis, Eagle Rock, and Zebulon Wirt,
Los Angeles, Calif.

Application July 21, 1932, Serial No. 623,734

1 Claim. (Cl. 173—259)

The present invention relates to terminal connections for electrical cables such as are used with wet batteries in joining or clamping such a cable to a battery binding post.

Connections of this type are ordinarily provided with a cable insert and with clamping members which may be placed about a battery binding post or other electrical contact and secured thereto. For ease of manipulation these connections are usually made from a soft metal alloy so that the clamping members may be easily spread apart and readily removed from the binding post. In order to hold the clamping members contracted about a binding post a bolt 5 is usually thrust through the clamping members and the desired contraction secured by screwing a nut upon the threaded end of the bolt.

Because of the soft metals from which these connections are ordinarily made, they are subject to corrosion and oxidation, especially from the action of acids used in batteries. This frequently results in one clamping member becoming frozen to the other member because of this chemical activity, so that, even with removal of the bolt, the clamping members cannot be separated from the binding post without the use of some tool to pry them apart. Consequently, binding posts, battery plates, and even the connections themselves are often badly damaged in the removal of these connections.

A principal object of the present invention is to provide means not only to contract the clamping members about a binding post but to expand these clamping members or force them away from the battery posts by a simple manipulation so that the connections may be removed with ease and without danger of injury to either the battery or the connection.

These and other objects will become apparent from a consideration of the following description and accompanying drawing in which

Fig. 1 is a plan view of a connection showing a bolt inserted through the clamping members and holding them in contracted relationship;

Fig. 2 is a sectional view of Fig. 1 with the bolt removed;

Fig. 3 is a cross section of the connection viewed on line 3—3 of Fig. 1.

Figs. 4 and 5 are sectional views of modified forms of the invention; and

Fig. 6 is a sectional view taken on line 6—6 of Fig. 4.

The connection of the present invention comprises body portion 10 which has the usual cable insert 11 and the outwardly bowed binding post

clamping members 12 and 13 which are shaped to fit tightly about an ordinary binding post 14.

Each of these clamping members has a lug 15 and 16, respectively, which is apertured to receive a bolt 17. In the embodiment of the invention as disclosed in the drawing, lug 16 has a smooth bored aperture through which extends bolt 17. This bolt is rotatably mounted in the lug 16 aperture and held therein by means of a bushing 18 which is rigidly affixed to said bolt adjacent lug 16 in any desirable manner, such as by welding or by pins 20. The aperture in lug 15 is threaded to form a receptive means for the threaded end 19 of the bolt. The aperture in lug 16 has, preferably, a smooth bore to afford easy rotation therein for the bolt 17.

By tightening the bolt into the threaded aperture in lug 15 the clamping members are contracted about the binding post 14. Upon reversing the tightening movement of this bolt, 20 to loosen the same, it is evident that the clamping members must be expanded away from the binding post as the bolt 17 is withdrawn from the lug 15 aperture. In order to facilitate movement of this bolt the head adjacent lug 25 16 may be of any desirable size or shape to interfit with an ordinary wrench. By this novel means we do away with the necessity of removing the bolt from the clamping members in order to expand the same and afford a simplified method of spreading the clamping members while loosening the bolt.

In order to facilitate the removal of the clamp we prefer to make the same from a soft metal alloy so that the clamping members may be spread readily. Or the connection may be made from two pieces interlocking at the base of the clamping members 12 and 13.

Clamping members 12 and 13 preferably are semi-circular in shape so as to completely enclose a binding post when contracted. Lugs 15 and 16 preferably extend outwardly from said clamping members on diametrically opposite sides of the same and tangential thereto. With this construction lugs 15 and 16 are substantially spaced apart allowing ample room for the bushing 18 therebetween. The spacing of the lugs in this manner likewise insures maximum contraction of the clamping members since their semi-circular configuration forces them to close tightly prior to any possible meeting of lugs 15 and 16.

Cable insert 11 may be of any desired shape according to the requirements of the cable terminal and may be so placed upon the connec-

tion that the cable may approach the same from any desired direction. If the cable insert is too large, suitable smaller bushings may be placed therein to reduce its size or the insert may be threaded to receive a threaded cable terminal. As shown in Fig. 3, the body portion has a split 20' adjacent the cable insert 11 so that the insert may be enlarged or contracted as desired. A screw 21 is provided to tighten the insert 11 about a cable terminal.

10 As examples of modified structures embodying the present invention, we have inserted Figs. 4, 5 and 6.

Fig. 4 discloses a modification in which the 15 body portion is divided into two parts, the division being made at the base of the clamping members 12 and 13. Clamping member 13 is made separate from the remainder of the body portion and has a rearwardly extending projection 25 which is adapted to fit into a hook-like portion 26 of the body and which is provided with a receiving groove 27 for holding the projection 25. The projection 25 at its base 28 should fit snugly within the groove 27 but may 20 decrease in size at its extremity 29 to provide a pivot for the clamping member. The clamping member 13 may be affixed to the body portion 10 prior to the placing of the connection about a binding post, or, after the body portion 30 has been placed about a post, clamping member 13 may be slid down over the post into its proper position.

A further modification may be seen in the 35 means for contracting and expanding the clamping members. The apertures in lugs 15 and 16 are provided with left hand and right hand threads respectively to receive a bolt 17 having threaded end members for coacting with these threaded apertures. Obviously, the turning of the bolt 17 in one direction within these 40 apertures will contract the clamping members, and a reversal of the bolt movement will expand the same. An opening 30 may be made through the center of the bolt, and radial thereto, to provide for the insertion of a pin for ease 45 of turning the same. Other means such as a nut or pin may be provided in lieu of the hole 30.

If desired, the extremity 29 of the projection 50 may be rounded as shown in Fig. 6 so as to facilitate ease in assembling the connection. This permits the part insertion of the threaded bolt 17 within each of the lug apertures before 55 engaging the projection 25 within the groove 27. Clamping member 13 may then be swung into its proper position using bolt 17 as a pivot. In order to secure a tight fit within the groove 27 of projection 25, the rounded extremity 29 should describe an arc the radius of which will

extend from the center of the lug apertures to the midpoint of the groove 27. By so constructing the projection 25, clamping member 13 may easily swing into and out of engagement with the remainder of the body portion and about 5 the partially engaged bolt 17 as a pivot.

Fig. 5 discloses a still further modification of the present invention in which a portion of the connection is utilized both for supplying the cable insert and for one of the clamping member lugs. As is seen in the drawing, the body portion comprises a combination cable insert and clamping member 35 in which is included the cable insert 11, the clamping member 12 and the clamping lug 15. Outwardly from this 15 body portion extends the circular clamping member 13 having its clamping lug 16.

The clamping members may be contracted and expanded in the manner heretofore described or a further modification, as disclosed 20 in Fig. 5, may be employed. Bolt 17 is provided with a circumferential channel 36 adjacent its head. The aperture in lug 16 is provided with a smooth bore to receive this channeled portion of the bolt and is rotatably but fixedly mounted 25 therein by means of a pin 37 which extends downwardly through lug 16 and rides in the channel 36 within the lug aperture. The aperture in lug 15 is threaded as in Fig. 1 to receive the threaded end 19 of the bolt. The contraction and expansion of the clamping members 30 will result by the turning or reversing of the bolt in the apertures as has heretofore been described.

Certain embodiments of the present invention 35 have been set forth herein for the purpose of exemplification, but the invention may be used in other structurally modified forms coming 40 equally within the spirit and scope of the appended claim.

We claim:

A battery connection, comprising a body portion having a cable connection, a battery terminal clamping member on said body portion, a hook-like keeper member on said body portion, 45 a second and separate clamping member having a flange for engaging said keeper member, and a clamping rod having oppositely threaded ends engaging complementary female threads in the clamping member on said body portion 50 and in said separate clamping member respectively, said rod being provided with intermediate means for permitting rotation of said lug, and said second clamping member being rotatable about said rod into position in engagement with 55 said keeper.
